Primary Examiner — Joseph Kukella*Assistant Examiner* — Lavon M. Amerson(74) *Attorney, Agent, or Firm* — Schwegman Lundberg & Woessner, P.A.(57) **CLAIM**

The ornamental design for a motor hub, as shown and described.

DESCRIPTION

FIG. 1 is a top perspective view of a motor hub showing my new design according to a first embodiment;

FIG. 2 is a bottom perspective view thereof;

FIG. 3 is a top view thereof;

FIG. 4 is a bottom view thereof;

FIG. 5 is a left view thereof;

FIG. 6 is a right view thereof;

FIG. 7 is a front view thereof; and,

FIG. 8 is a bottom view thereof.

The portions of the motor hub shown in broken lines form no part of the claimed design.

1 Claim, 8 Drawing Sheets(56)
